UNITED STATES PATENT OFFICE.

AUSTIN W. HOOVER AND ROBERT WINTER, JR., OF IRWIN, PENNSYLVANIA.

DESIGN FOR A TONE ARM.

Application filed July 27, 1921. Serial No. 488,024. Term of patent 3½ years.

To all whom it may concern:

Be it known that we, AUSTIN W. HOOVER and ROBERT WINTER, Jr., citizens of the United States, and residing at Irwin, in the county of Westmoreland and State of Pennsylvania, have invented a certain new, original, and ornamental Design for a Tone Arm, of which the following is a specification, reference being had to the accompanying drawing, forming a part thereof.

The figure is a perspective view of a tone arm showing our new design.

We claim:—

The ornamental design of a tone arm, substantially as shown.

AUSTIN W. HOOVER.
ROBT. WINTER, JR.
